UNITED STATES PATENT OFFICE.

CHARLES SHEER, OF CORONA, NEW YORK.

DESIGN FOR A FINGER-RING.

55,335.

Specification for Design.

Patented May 25, 1920.

Application filed December 17, 1919. Serial No. 345,655. Term of patent 14 years.

To all whom it may concern:

Be it known that I, CHARLES SHEER, a citizen of the United States of America, and a resident of Corona, in the county of Queens and State of New York, have invented a new and original and ornamental Design for Finger-Rings, of which the following description, in connection with the accompanying drawing, is a specification.

In the drawing, Figure 1 represents a plan view of the ring looking toward the setting and Fig. 2 shows the ring in elevation.

I claim as my invention.

The ornamental design for a finger ring as shown.

CHARLES SHEER.
